(74) Attorney, Agent, or Firm—Pepper Hamilton LLP

(57) **CLAIM**

The ornamental design for a bottle, as shown and described.

DESCRIPTION

FIG. 1 is a perspective view of a top side of a bottle according to the invention.

FIG. 2 is a right side view of the bottle of FIG. 1.

FIG. 3 is a top view of the bottle of FIG. 1; and,

FIG. 4 is a perspective view of an alternative embodiment of a bottle according to the invention.

The broken line showing is for illustrative purposes only, and forms no part of the claimed design.
